MULTISTAGE CENTRIFUGAL PUMP

William H. Curtis, North Hollywood, Calif., Leslie L. Aspelin, Cleveland Heights, Ohio, and James C. Carter, Pasadena, Calif.; said Curtis and said Aspelin assignors to Thompson Products, Inc., Cleveland, Ohio, a corporation of Ohio, and said Carter assignor to The J. C. Carter Company, Pasadena, Calif.

Application February 15, 1951, Serial No. 211,104

20 Claims. (Cl. 103—97)

1

This invention relates to improvements in centrifugal pumps and more particularly relates to improvements in multistage centrifugal pumps particularly adapted to pump jet fuel and the like.

A principal object of our invention is to provide a novel and efficient form of multistage centrifugal pump arranged with a view towards automatically delivering a constant volume of fluid.

A further object of our invention is to provide a new and improved form of multistage fluid pump automatically controlling the discharge volume of the pump by variations in pressure drop across an orifice, from a predetermined normal constant pressure drop, to attain a constant pressure drop regardless of variations of flow rate of the pump.

Still another object of our invention is to provide a novel form of control means for a multistage centrifugal pump automatically activating or deactivating certain stages of the pump, by variations in pressure drop across an orifice at the discharge side of the pump, from a predetermined constant pressure drop.

Still another object of our invention is to provide a new and improved control means for controlling the discharge pressures of a fluid pump by utilizing pressures on the intake side of the pump to render certain of the stages of the pump active or inactive and in controlling the distribution of pressure to the various stages of the pump by variations in pressure drop across an orifice at the discharge side of the pump from a predetermined constant pressure drop.

A further object of our invention is to provide a new and improved form of multistage centrifugal pump together with means controlled by the pressure drop across an orifice at the discharge side of the pump, for progressively activating or de-activating the stages of the pump as the pressure drop varies from a predetermined normal constant pressure drop.

A still further and more detailed object of our invention is to provide a new and improved form of multistage centrifugal pump for jet fuel and the like having a plurality of impellers and associated diffusers forming the stages of the pump, wherein the activation or de-activation of the several stages of the pump is effected by establishing a pressure differential on opposite faces of certain of the diffusers of the pump or by bringing the pressures into equilibrium, and wherein the variation of pressure differential is controlled by variations in rate of flow of the

2

pump from a predetermined required rate of flow.

Another object of our invention is to provide a multistage centrifugal pump particularly adapted for jet fuel and the like including a plurality of alternately arranged impellers and diffusers together with a control means for progressively rendering the stages of the pump active or inactive by reducing the pressure against one face of certain of the diffusers and thereby creating a differential in pressure on opposite sides thereof to render said diffusers active, and by balancing the pressure on opposite faces of certain of said diffusers to allow said diffusers to freely rotate with said impellers and become inactive.

In carrying out our invention, we alternately mount a plurality of impellers and diffusers on a power driven shaft within a housing and provide an inlet into said housing communicating with the first of said impellers and an outlet from said housing communicating with the last of said diffusers, and rotatably drive the impellers by power. We also progressively render the diffusers active or inactive upon variations in rate of flow of the pump from a predetermined constant rate of flow. We further utilize pressure in the intake passageway of the pump, which may be greater or less than atmospheric pressure, to establish a differential in pressure on opposite faces of the diffusers, causing the diffusers to be forced against the casing of the pump and held from rotation by frictional engagement therewith and become active, and vary the pressure differential, to create a balanced pressure on opposite sides thereof, allowing the diffusers to rotate with the impellers, by the pressure of the fluid directed thereon by said impellers, and rendering said diffusers inactive. We further control the creation of a pressure differential on opposite sides of the diffusers by a servo control means operated by variations in rate of delivery of the pump, and by distributing valve means controlled by the servo control means and operated by pressure derived from the first stage of the pump.

These and other objects of our invention will appear from time to time as the following specification proceeds and with reference to the accompanying drawings wherein:

Figure 1 is a partial, longitudinal sectional view taken through a pump constructed in accordance with our invention and through a servo control means therefor controlling the activation and deactivation of the several stages of the

pump and diagrammatically showing a variable orifice and throttle valve in the discharge pipe from the pump;

Figure 2 is a fragmentary transverse sectional view taken through the pump, showing certain details of one of the pump impellers;

Figure 3 is a fragmentary transverse sectional view taken through the pump, showing certain details of one of the diffusers;

Figure 4 is a transverse sectional view taken substantially along line IV—IV of Figure 1, and showing certain details of the fluid connections to a diffuser for one stage of the pump, for unbalancing the pressure on opposite sides of the diffuser;

Figure 5 is a diagrammatic view illustrating a modification in the control for the pump; and

Figure 6 is a diagrammatic view illustrating another modification in the control for the pump.

Referring now in particular to the embodiment of our invention shown in the drawings, the pump is shown as comprising a housing 10 having a central portion 11 of a generally cylindrical or drum like form, with an intake end cap 12 threaded on one end thereof and a discharge end cap 13 threaded on the opposite end thereof. The end caps 12 and 13 are suitably sealed to prevent the leakage of fluid thereby, as by O rings indicated generally by reference character 14. A drive shaft 15 is journaled in the intake and the discharge end caps 12 and 13 of the housing 10 on ball bearings 16 and 17. The end of the shaft 15 adjacent the intake end cap 12 is internally lined, as indicated by reference character 19, to afford a means for rotatably driving said shaft by an external driving means, such as the engine of the aircraft, or a separate motor (not shown). A suitable sealing means, herein diagrammatically shown as being a sylphon bellows seal is provided in the end caps 12 and 13 to prevent the leakage of fluid from within the pumping chamber along the shaft and outside of the ends of the casing.

The intake end cap 12 has an inlet port 22 formed therein and communicating with the intake side of an impeller 23, mounted on the shaft 15 for rotation therewith. An intake pipe 24 is herein shown as being threaded in the intake end cap 12 in communication with the port 22. The intake cap 12 of the housing 10 is likewise shown as having an inner wall 25 formed internally therewith, which substantially conforms to the form of blades 26 of the impeller 23, and confines the fluid to said blades for discharge from the periphery of a disk 27 of said impeller.

The disk 27 of the impeller 23 is herein shown as having an inner hub portion 29 pressed on a tapered split bushing 30 on the shaft 15. This bushing serves to secure said impeller to said shaft for rotation therewith. The blades 26—26 extend from the intake side of the disk 27 beyond the periphery thereof and are shown as being of a generally spiral form and impel the liquid for discharge across the periphery of said disk.

Impellers 33, 34 and 35, like the impeller 23, are likewise spaced along and mounted on the shaft 15 for rotation therewith on split bushings 36, 37 and 38 respectively, in the same manner the impeller 23 is mounted on said shaft. Diffusers 39, 40, 41 and 42 are journaled on the shaft 15 between and in association with the respective impellers 23, 32, 34 and 35 on the discharge sides thereof, for free rotation with respect to said shaft. The last of said diffusers is shown as being in communication with a discharge port 44,

formed in the discharge end cap 13 of the housing 10, for the discharge of fluid under pressure therefrom.

The diffuser 42 is shown as having an inclined annular disk 46 of a generally frusto-conical form adjacent and extending parallel with an inclined face 47 of an annular insert 49 of the central housing 11. Said insert may be a casting suitably mounted within the central cylindrical portion 11 of the housing 10, as by pressing. The outer end of said insert abuts the discharge end cap 13. The annular insert 49 also forms a continuation of the discharge port 44 and conducts fluid discharged from the diffuser 42 thereto. The insert 49 also has an annular passageway 50 opening to the inside of the central housing 11 and having a plurality of angularly spaced passageways or ports 51—51 opening through the face 47 to the adjacent face of the disk 46.

The diffusers 40 and 41 like the diffuser 42 have annular disk portions 52 and 53, respectively, conforming to the inclined plane annular surfaces 54 and 55 of annular inserts 56 and 57, respectively. The inserts 56 and 57 conform generally to the outer margins of the respective impeller blades and diffuser disks and have outwardly opening annular passageways formed therein, opening to the inner periphery of the central housing 11. Said passageways form annular passageways, having ports 59 and 60 opening therefrom through the faces 54 and 55 respectively and communicating with the respective diffuser disks 52 and 53 for establishing a differential in pressure on opposite faces of said disks, as will hereinafter more clearly appear as this specification proceeds.

The diffuser 39 is herein shown as being shorter than the diffusers 40, 41 and 42 and as having vanes 63—63 extending from frusto-conical annular disk 64. Stationary diffusing vanes 65—65 are herein shown as being formed integrally with an annular insert 66 somewhat similar to the inserts 56 and 57 mounted within the central housing portion 11. The stationary diffusing vanes 65 form continuations of the vanes 63—63 and assure that the first stage of the pump will always be partially active. The annular insert 66 extends between the diffuser 39 and impeller 33 and confines liquid to the blades of said impeller and has an advance wall 69 having the disk 64 recessed therein. Low pressure ports 70—70 lead through said wall from said disk to an annular passageway 71 formed between said insert and the inner periphery of the central housing 11 and afford a means for reducing the pressure on the face of said disk adjacent the wall 69 and creating a differential in pressure on opposite faces of said disk to render the diffuser 39 active.

The diffusers 39, 40, 41 and 42 are all of a similar construction with the exception that the diffuser 39 is shorter than the succeeding diffusers, so a description of the diffuser 42 will suffice for a description of all of said diffusers. The diffuser 42 includes the frusto-conical annular disk 46 spaced radially from the shaft 15 at its inner end, and providing a fluid passageway between a hub 73 of said diffuser and the inner periphery of the disk 46. (See Figures 1 and 3.) A plurality of spaced diffuser vanes 74—74 are mounted on the disk 46 and hub 73 and extend therefrom towards the associated impeller 35. The diffuser vanes 74—74 have opposite faces 75 and 76, which diverge from an

apex spaced outwardly from the shaft 15 and inwardly of the outer periphery of the hub 13 and are of a generally spiral form having fluid passageways 17 therebetween. The vanes 14-14 are suitably secured at their inner ends to the hub 13, and at their sides opposite said hub to the disk 46. The hub 13 is journaled on the shaft 15 on a bearing 79, herein shown as being a plain bearing. Clearance is provided between the outer periphery of the disk 46 and the inner periphery of the face 47 of the associated insert 49, to allow fluid to leak past said disk and pass along the face of said disk adjacent the ports 51 into said ports and the passageway 50, and balance the pressure on opposite sides of said disk and allow said diffuser to freely rotate on the shaft 15, rendering the respective stage of the pump inactive when so rotating.

It will be understood from the foregoing that the impeller 23, stationary diffusing vanes 65-65 and the diffusing vanes 63-63 of the diffuser 39 form the first stage of the pump, and that this stage of the pump is always activated due to the fact that the vanes 65-65 are stationary. This is to assure that there will always be some discharge pressure on the first stage of the pump, to insure activation of the servo-controls, controlling activation of the various stages of the pump.

The impeller 33 and diffuser 49 form the second stage of the pump, while the impeller 34 and diffuser 41 form the third stage of the pump, and the impeller 35 and diffuser 42 form the last stage of the pump. All of these succeeding stages of the pump may be progressively activated or de-activated as conditions arise, to control the discharge pressure of the pump and to effect the gradual increase or decrease of the discharge pressure, to the predetermined normal pressure.

Activation or deactivation of the successive stages of the pump is shown in Fig. 1 as being attained by servo-control means operated by the pressure drop of fluid passing through a restriction 80 in a pipe 81, leading from the discharge port 44 and supplying the fuel nozzles (not shown) of the engine with fuel. The restriction 80 has an orifice 80a therein, which may either be a fixed or a variable orifice, to create a predetermined difference in pressure on opposite sides of said restriction in accordance with the fuel demand.

As shown in Fig. 1, a needle valve 80b is associated with the orifice 80a on the downstream side of the restriction 80 to vary the area of said orifice in accordance with upward or downward drift in engine speed, to decrease or increase the area of the orifice in accordance with engine needs. The needle valve 80b may be operated from a governor 80c for the engine through a pivoted arm 80d, in a manner well known to those skilled in the art so not herein shown and described in detail.

It should here be noted that while we have shown a needle valve to vary the orifice area, that a needle valve need not be used and a variable orifice of the leaf or iris type, or any other form of variable orifice may be used instead.

It should further be understood that the orifice 80a need not be variable, but may be a fixed orifice and that where the orifice is fixed a throttle valve 80e, as shown in Figure 5, may be provided downstream of the orifice 80a in a continuation of the pipe 81, to attain a substantially constant discharge volume for the pump.

A pipe 83 is connected with the pipe 81 on the

upstream side of the restriction 80. This pipe is connected to one end of a valve casing 84, to supply fluid under pressure thereto and move the piston valve 85 along a valve chamber 86 against a preloaded spring 87 in a direction, which is shown in Figure 1 as being to the left. A pipe 88 is connected from the downstream side of the restriction 80 to the opposite or left hand end of the valve casing 84. The pressure in the pipe 83 plus the force exerted by the spring 87, balances the pressure of fluid exerted through the pipe 88, when the pressure drop across the restriction 80 is a predetermined constant pressure drop. A pipe 89 connects the intake pipe 24 with a low pressure passageway 90 formed in the valve casing 84. The pipe 89 leads to annular grooves 91 formed adjacent opposite ends of the valve chamber 86 and closed by lands 92-92 on opposite ends of the valve piston 85. A pipe 95 leads from a port 97, communicating with the discharge of the first stage of the pump, which is always partially active. The pipe 95 is connected with an annular port 97 formed in the valve chamber 86, intermediate the ends thereof. The port 97 is closed by a land 98 of the valve piston 85. An annular port 100 is provided in the valve chamber 86 to the left of the port 97, and herein shown as being substantially intermediate the ports 91 and 97. A pipe 101 is connected from the port 100 to one end of a valve casing 102 for a distributor valve 103. In a like manner, an annular port 104 is provided in the valve chamber 86 to the right of the annular port 97, and herein shown as being spaced equally between the ports 97 and 91. A pipe 105 connects the port 104 with the opposite end of the valve casing 102 from the pipe 101. The valve casing 102 has a cylindrical valve chamber 106 with a hollow valve element 107 slidably mounted therein. The valve element 107 is herein shown as being of a generally cylindrical form, closed at its opposite ends so that fluid under pressure exerted on either end of said valve element will move said valve element along said casing in an obvious manner.

A pipe 109 connects the intake or pipe 24 with a chamber 110 formed in the valve casing 102 and communicating with the valve chamber 106 through a passageway 111 and an annular port 112. The valve chamber 106 has annular ports 113, 114, 115 and 116 formed therein communicating with pipes 117, 118, 119 and 120, respectively. These pipes communicate with the respective suction ports 50, 59, 69, and 51 for unbalancing the pressure on opposite sides of the respective diffusers under control of the pressure drop across the orifice 80.

The hollow valve element 107 is likewise provided with ports 121, 122, 123, 124, 125 leading to and from the hollow center thereof. The first four of said ports are herein shown as being progressively wider from the right to the left hand end of said valve element. The port 125 is adjacent the right hand end of the valve element 107 to the right of the port 121 and affords a communication from the groove 112 to the hollow inside of said valve element to impose suction pipe pressure therein.

In describing the operation of the pump of our invention and the control means therefor, for maintaining a substantially constant pressure drop across the orifice, regardless of variations in the rate of flow of fluid in the pump, the method of controlling a single stage of the pump, as for example, the final or fourth stage of the pump will first be described. With the

impeller 35 rotating at a normal rate of speed and the valve element 107 in the position shown in Figure 1, the passageway 50 and ports 51-51 will be connected with the intake pipe 24. This will create a differential in pressure on opposite sides of the diffuser disk 46 forcing said disk into engagement with the inclined face 47 of the annular insert 49 and holding said disk from rotation by the friction between said disk and face. The last stage of the pump will then give its full discharge capacity. If, however, the diffuser 42 is allowed to rotate freely, as when pressure on opposite sides of the disk 46 is equal, it will rotate with the impeller 35 at substantially the same speed of rotation as the impeller, by the impact of the fluid discharged from said impeller with a high tangential velocity against the diffuser vanes. Upon rotation of said diffuser the centrifugal effect thereof will oppose and balance off the pressure generated by the impeller 35, and thus reduce the discharge pressure of the fourth stage of the pump to nearly zero. When this occurs this stage of the pump is deactivated.

The diffuser 42, however, is free to rotate only if the fluid pressure on both sides of the disk 46 is equal. Hence, if the passage 50 and ports 51-51 are closed from communication with the low pressure of port 116, fluid will leak to the side of the disk 46 adjacent the inclined face 47 of the insert 49 and the pressures on both sides of said disk will balance. Under this condition the disk 46 and diffuser 42 will freely rotate. If, however, the passage 50 and ports 51-51 are opened to communication with a low pressure port such as the pressure in the pipe 24 which may be below atmospheric pressure, chamber 110 and hollow inside of the valve element 107 through the port 116, the pressure of the fluid in the pump will force the disk 46 against the face 47 of the casting 49 and the frictional resistance between said disk and casting will hold the diffuser 42 from rotation. The vanes of said diffuser will then act as flow straighteners and direct the fluid into the discharge port 44 and the last stage of the pump will be fully activated.

If, however, pressure in the passageway 50 and ports 51-51 should only be partially released, the pressure differential across the disk 46 will be less than that required to fully prevent rotation of said disk and diffuser. Said diffuser will rotate at a slower rate of speed than that of the impeller 35. This will result in a reduced discharge pressure for this stage of the pump. It will thus be apparent that the discharge pressure of each of the several stages of the pump is a direct function of the pressure differential across the diffuser disks.

In considering now the operation of all of the stages of the pump and the control means therefore, it should be recalled that the first stage of the pump is never completely deactivated by reason of the fact that the vanes 65-65 are always stationary and will serve to partially redirect the fluid delivered by the impeller 23, even when the inner diffuser vanes of the diffuser 39 are free to rotate. This assures that there will always be a discharge pressure from the first stage of the pump to activate the servo-controls, to control the discharge pressure of all of the stages of the pump.

As illustrated in Figure 1 of the drawings the valve element 107 is positioned to exert pressure in the passageway 50 and ports 51-51 through the pipe 120, annular port 116, hollow interior of

the valve element 107 and ports 125 and 112 communicating with the suction or intake pipe 24. With the valve cylinder 107 in this position, the discharge pressure in the port 44 and pipe 81 will be that due to the partial activation of the first stage of the pump due to the stationary vanes 65, and the full activation of the last stage of the pump. The diffusers 39, 40 and 41 will then be free to rotate, rendering the second and third stages of the pump inactive, and the first stage of the pump partially active.

With the pump operating under these conditions, assume that the orifice is variable and controlled by an external source, such as an engine governor 80c, and assume a downward drift of engine speed calling for more fuel. The governor in response to the reduced engine speed will cause the area of orifice 80a to increase. The pressure drop across the orifice 80a will then decrease and be less than the value required to balance the force of the spring 87. This will unbalance the forces acting on opposite ends of the valve piston 85 causing said valve piston 85 to move to the right. This will open the port 97 to supply fluid under pressure to the left hand end of the valve element 107, the port 108 and the pipe 101. The right hand port 90 will also be opened to supply pressure at the pressure of fluid in the intake pipe 24 on the right hand end of the valve cylinder 107, through the port 104 and pipe 105. Since pressure in the intake pipe 24 is always less than the discharge pressure of the first stage of the pump, the valve element 107 will move to the right. The port 123 will then register with the annular port 115, and the ports 60-60 will be connected with the intake pipe 24 through the pipe 119. A pressure differential will thus be set up across opposite faces of the disk 53 of the diffuser 41, with the result that said diffuser will come into frictional engagement with the inclined face 55 of the insert 57 and will stop its rotational movement and activate the third stage of the pump.

If the discharge pressure of the pump resulting from the activation of the fourth and third stages and partial activation of the first stage is still insufficient to bring the pressure drop across the orifice 80a, to the predetermined constant value, the piston 85 will remain in its right hand position and the valve cylinder 107 will continue to move toward the right and bring the port 122 into registry with the annular port 114, thereby reducing pressure in the ports 59-59 and establishing a differential in pressure on opposite faces of the disk 52 of the diffuser 40, rendering said diffuser active in the hereinbefore described manner.

This process will continue until the rate of fluid flow in pipe 81 is sufficient to establish the predetermined pressure drop across orifice 80a, now enlarged, or until the valve element 107 brings the port 121 into registry with the annular port 113 and connects the ports 70-70 with the intake 24, thereby stopping rotation of the diffuser 39 and completely activating the first stage of the pump.

Since the pump is driven from the engine of the aircraft the pump speed will also have drifted downward in the same proportion as engine speed, so the reactivation of pumping stages must continue until the effect of their reduced pump speed has also been overcome.

It should here be noted that the pump is so designed that it should never be necessary to fully activate all of the stages, to deliver the re-

quired pressure to the discharge port 44. A reserve capacity is thus available to take care of emergency conditions and possible unavoidable errors which may be made in the calculations required to determine the capacity of the pump.

An increase in cross-sectional area of the orifice 80a will permit an increase in volume of fuel passing through it in accordance with the normal predetermined pressure drop, thus leading to the restoration of engine speed to its original preset value. This additional volume of fuel, however, must pass through the fuel nozzles (not shown) for the engine, and since these nozzles mainly have the characteristics of fixed orifices, said increased volume of fuel can only be obtained by an increased discharge pressure from the pump. Therefore, additional pumping stage activation will continue until the discharge pressure has been reached which will produce the normal volume of flow through the orifice 80a and the fuel nozzles required to restore the pressure drop across the orifice 80a to its predetermined value. At this point the forces acting on opposite ends of the piston valve 85 will have returned it to its normal central position, and the piston will again be in equilibrium.

In the event of an upward drift in engine speed, the cross-sectional area of the orifice 80a will be reduced, and the pressure drop across said orifice will change so that it exceeds the predetermined normal value. Then the pressure acting upon the right hand end of the valve 85 will exceed the combined force of the spring 87 and the pressure of fluid acting on the left hand end of said valve. The valve piston 85 will then move towards the left. Pressure from the pipe 95 and the first stage of the pump will then be exerted on the right hand end of the valve cylinder 107 through the pipe 105, and a reduced pressure will be exerted on the left hand end of said valve cylinder through the pipe 101. The valve cylinder 107 will then move to the left and progressively de-activate the stages of the pump starting with the first stage if said stage has been activated, and successively closing one or more of the respective annular ports 113, 114, 115, and 116 in the order named, with the de-activation of the pumping stages until equilibrium is reached.

It should here be noted that the area of the port openings of the valve element 107 is such that movement of said valve element along the valve chamber 106 in either direction, progressively opens and closes the ports 113, 114, 115 and 116, resulting in a progressive activation and deactivation of the various stages of the pump.

It will further be understood that the coefficient of friction between the disks 64, 52, 53 and 46 of the respective diffusers 39, 40, 41 and 42 may be varied by the use of suitable friction materials to vary the braking effect due to the frictional engagement between the parts. The maintaining of a small amount of fluid leakage around the respective diffuser disks from the pumping chambers to the ports or passageways 70, 59, 60 and 51 may vary the braking effect between the diffusers and stationary parts of the casing. This will, of course, be dependent upon the area of port openings in the valve 103. Thus by suitably contouring the opening edges of the ports 121, 122, 123, and 124 in the valve element 107, the rate of frictional engagement and braking effect of the diffusers, depending upon the coefficient of friction thereof, may be built up relatively rapidly or gradually and may be halted

at any point. The activation as well as the deactivation of any stage can thus be caused to take place at any desired rate and where it takes place gradually, if the predetermined pressure drop across the restriction is reached during a period of transition, the particular stage in which the transition takes place will remain only partially activated, until a change in pressure drop occurs.

It may thus be seen that since the activation and deactivation of the various stages is under fluid control and is attained by the creation of a differential in pressure across the diffuser disks, or by the balancing of pressure on opposite sides thereof, that the activation and deactivation of the various stages of the pump may be progressive and gradual, resulting in a gradual increase or decrease in pump pressures controlled solely by the variations in pressure drop across the orifice 80a, from a predetermined constant pressure drop.

Referring now to Figure 5, diagrammatically showing the orifice 80a as being fixed and showing a throttle valve 80e mounted in the pipe 81 downstream of the orifice 80a and assuming the pump is driven from the engine of the aircraft and thus varies in speed in accordance with the speed of the engine, a constant discharge volume within narrow limits may be attained throughout the designed range of pump speeds and discharge pressures, which will depend solely upon the area of the fixed orifice 80a and the force imposed upon the piston valve 85 by the spring 87.

With the pump in normal operation at normal speed to deliver the desired discharge volume and with the throttle valve 80e in some mid position, further closing of said valve will result in a reduced rate of flow in the pipe 81 and through the orifice 80a, resulting in a reduction of the predetermined pressure drop across the orifice 80a, to a below normal drop. This reduction in pressure drop will unbalance the forces acting upon opposite ends of the piston valve 85 and will cause said piston valve to move to the right. This will activate additional stages of the pump in the manner previously described and will raise the discharge pressure in the pipe 81 until the rate of flow required to produce the predetermined pressure drop across the orifice 80a shall have been reached. At this point the unbalanced forces acting on opposite ends of the piston valve 85 will be in equilibrium and said piston valve will be in its normal mid position.

Opening of the throttle valve 80e beyond the aforementioned mid position will allow an increase in volume of fluid to pass through said valve, resulting in an increased velocity through the orifice 80a and a greater than normal pressure drop across said orifice. When this condition arises, the unbalanced forces acting upon opposite ends of the piston valve 85 will cause it to move to the left. This will result in the deactivation of the pumping stages until the discharge pressure in the pipe 81 shall have reached the value necessary to produce the rate of flow through the orifice 80a required to attain the predetermined pressure drop across the orifice. When this pressure drop is attained the unbalanced forces acting upon opposite ends of the piston valve 85 will be in equilibrium, and said piston valve will return to its normal mid position.

It is obvious that a downward drift in pump speed with no change in the throttle opening,

11

will result in reactivation of the pumping stages by the same sequence of events previously described, and that in a contrary manner, an upward drift of pumping speed will bring about deactivating of the pumping stages by the sequence of events previously described.

In the form of our invention shown in Fig. 6, illustrating a modified form in which our invention may be embodied, the restriction 86 and orifice 86a have been removed from the pipe 81. A pipe 81a is shown, which instead of being connected with the fuel nozzles like the pipe 81, may be connected to a hydraulic load, such as a hydraulic motor (not shown) which requires variable volume of supply at constant pressure over and above the pump inlet pressure. In this form of our invention, the control of the pump is attained by the difference between inlet and discharge pressures, to obtain a constant pressure rise across the pump. The pipe 83 is shown as being eliminated and the left hand end of the valve casing 84 is connected to the suction pipe 24 through a pipe 129 and a pipe 130. The pipe 129 is shown as having an extension 131 leading to the atmosphere for purposes which will hereinafter more clearly appear as the specification proceeds. A valve 132 is provided in the extension 131 to maintain said extension closed. A valve 133 is likewise provided in the pipe 130 to disconnect the lefthand end of the valve body 84 from the intake pipe 24 when desired, for purposes which will hereinafter more clearly appear as this specification proceeds.

Assuming that the lefthand end of the valve body 84 is connected to the intake pipe 24 and that the valve 132 is closed, and the valve 133 is open, a reduced pressure is maintained on the lefthand end of the valve piston 85 in accordance with the intake pressure of the pump and the force exerted by the spring 87. In this form of our invention the spring 87 may be designed to exert sufficient force upon the lefthand end of the piston valve 85 to require the full predetermined pressure rise across the pump, to move said piston valve to the left against the force exerted by said spring.

With this arrangement any increase in volume demanded by the hydraulic load, or any decrease in pump speed will, by reason of lowering the pressure rise across the pump, unbalance the forces acting upon the opposite ends of the piston valve 85, causing said piston valve to move to the right and progressively activate the various stages of the pump until the pump produces the demanded volume at the required pressure.

If, however, the hydraulic load demand is for a reduced volume, or if the pump speed has drifted upward, the forces acting upon the ends of the piston valve 85 will be unbalanced in a contrary manner and the piston valve 85 will move to the left, causing the various stages of the pump to be deactivated until an equilibrium is reached.

Assuming now that the valve 133 is closed and the valve 132 is open. The lefthand end of the valve body 84 will then be open to the atmosphere. The spring 87 may be selected according to the gauge pressure desired. Upon any increase in volume demanded by the hydraulic load, or upon any decrease in pump speed, which results in a lowering of the pressure rise across the pump, the forces acting upon the opposite ends of the piston valve 85 will be unbalanced, causing said piston valve to move to the right and activating additional stages of the pump to

65

70

75

12

produce the demanded volume at the predetermined pressure in the manner hereinbefore described.

Where the hydraulic load demand is for reduced volume of fluid, or where the pump speed has drifted upward, the forces acting upon the opposite ends of the piston valve 85 will again be unbalanced so as to cause said piston valve to move to the left resulting in the deactivation of the additional stages of the pump until the delivery volume of the pump is reduced to the hydraulic demand.

It should be noted that in the form of our invention illustrated in Fig. 5 various springs may be substituted for the spring 87 to exert the required force on the lefthand end of the piston valve 85, to attain the required pressure rise across the pump, and that said spring may be adjustable from the exterior of the valve block, to adjust the pressure exerted by the spring to the pressure desired, or to the hydraulic volume demand. Said spring may be adjusted by any one of a number of well known methods operable from the exterior of the valve block which are no part of our present invention so are not herein shown or described in detail. The discharge pressure of the pump above the inlet pressure, or above atmospheric pressure, as the case may be, may then be adjustable within the predetermined range for the pumping unit between the stage of complete activation and complete deactivation.

It should further be understood that the valve assembly and body 84 may be completely eliminated and that the movement of the multiple ported valve element 107 may be controlled directly by manual means, or by any other well known means to accomplish the desired pressure and volume control.

It will be understood that modifications and variations may be effected without departing from the scope of the novel concepts of the present invention.

We claim as our invention:

1. In a constant delivery volume fluid pump, a housing, an inlet into said housing, an outlet therefrom, a shaft journaled therein, means for rotating said shaft, an impeller on said shaft in communication with said inlet, a diffuser journaled on said shaft for free rotation with respect thereto and including a rotatable disk having a plurality of diffusing vanes extending therefrom, a stationary housing portion extending along one side of said disk, fluid pressure passageways from said housing portion to said disk, and fluid pressure means controlled by the delivery flow of said pump and operable to reduce the pressure in said passageways and establish a differential in pressure on opposite faces of said disk and cause the pressure of the fluid within said pump to force said disk against said housing portion, holding said disk and diffuser from rotation, rendering the diffuser active, and also operable to equalize the pressure on opposite faces of said disk and allow said disk to freely rotate on said shaft, rendering said diffuser inactive.

2. In a fluid pump, a housing, an inlet into said housing, an outlet therefrom, a shaft journaled therein, means for rotating said shaft, an impeller on said shaft in communication with said inlet, a diffuser freely journaled on said shaft in communication with said impeller, said housing having a wall portion extending adjacent the opposite face of said diffuser from said impeller, a fluid passageway in said wall portion, a fluid

connection from said inlet to said passageway to reduce the pressure on the face of said diffuser adjacent said wall portion, enabling the fluid pressure on the opposite face of said diffuser to engage said diffuser with said wall portion and stop rotation thereof, fluid pressure operated valve means in said fluid connection, and fluid pressure connections from said discharge outlet to operate said valve means upon variations in flow in said outlet from a predetermined normal flow.

3. A constant delivery volume fluid pump comprising a housing, an inlet into one end thereof, an outlet from the opposite end thereof, a power driven shaft journaled therein, an impeller on said shaft in communication with said inlet, a diffuser freely journaled on said shaft in communication with said impeller and outlet, said housing having a wall portion extending along a face of said diffuser opposite from said impeller, a passageway leading through said wall portion to said diffuser, a fluid connection from said inlet to said passageway having fluid pressure operated valve means therein, a restricted orifice in said outlet, and fluid pressure connections from opposite sides of said orifice to said valve means, to operate said valve means upon changes in pressure drop across said orifice from a predetermined constant pressure drop, to establish a pressure differential on opposite faces of said diffuser rendering said diffuser active, or to balance the pressure on opposite faces of said diffuser, allowing said diffuser to freely rotate with respect to said shaft.

4. A constant volume fluid pump comprising a housing, an inlet thereinto, an outlet therefrom, a shaft journaled therein, an impeller on said shaft, a diffuser associated with said impeller and freely journaled on said shaft, said housing having a wall portion extending along the face of said diffuser opposite from said impeller and having a passageway leading therethrough, a restricted orifice in said outlet, and fluid pressure control means automatically operable upon variations in pressure drop across said orifice, to activate or render said diffuser inactive comprising a fluid connection from said inlet to said passageway having a fluid pressure operated valve therein, a second fluid pressure operated valve, fluid pressure connections from opposite sides of said restricted orifice to opposite ends of said second valve for operating said valve, and fluid pressure connections from said second valve to opposite ends of said distributor valve for operating said valve to reduce pressure on the side of said diffuser adjacent said wall portion.

5. A multistage fluid pump comprising a housing, an inlet thereinto, an outlet therefrom, a shaft journaled in said housing, a plurality of alternately arranged impellers and diffusers thereon, each impeller and associated diffuser forming a stage of the pump, said housing having wall portions extending along the faces of said diffusers opposite from their associated impellers, means operable by variations in rate of flow in said outlet, for progressively reducing the pressure on the faces of said diffusers adjacent said wall portions and enabling pressure of the pump to engage said diffusers with said wall portions, stopping rotation thereof and rendering said diffusers active.

6. A multistage fluid pump comprising a housing, an inlet into and an outlet from said housing, a drive shaft journaled in said housing, a plurality of impellers spaced along said shaft and

driven thereby, a plurality of diffusers freely mounted on said shaft between said impellers, each associated impeller and diffuser forming a stage of the pump, the first of said diffusers being of a lesser diameter than the remaining diffusers, and said housing having a plurality of stationary diffuser vanes in communication with the vanes of said first diffuser, assuring partial activation of the first stage of the pump at all times, said housing having wall portions extending along the faces of said diffusers opposite from said impellers, passageways in said wall portions, fluid pressure operated valve means operable to afford fluid communication with said passageways, and means operated by variations in rate of flow from a required rate of flow in said outlet to effect operation of said valve means to progressively afford communication with said passageways and progressively reduce the pressure in said passageways starting with the last stage of the pump and reduce the pressure on the faces of said diffusers adjacent said wall portions and hold said diffusers from rotation by frictional resistance against said wall portions, to activate said diffusers and the associated stages of the pump, and to close said passageways from fluid communication and accommodate the pressure on opposite sides of said diffusers to balance and permit free rotation of said associated diffusers and inactivate the associated stages of the pump.

7. In a multistage fluid pump comprising a housing, an inlet into and an outlet from said housing, a drive shaft journaled in said housing, a plurality of impellers spaced along said shaft and driven thereby, a plurality of diffusers freely mounted on said shaft between said impellers, the first of said diffusers being of a lesser diameter than the remaining diffusers, and said casting having stationary diffusing vanes forming a continuation of the vanes of the first of said diffusers, assuring partial activation of the first stage of the pump at all times, passageway means in said housing leading to the faces of said diffusers opposite from said impellers, a distributor valve, a connection from said inlet to said valve, and means for operating said distributor valve to progressively create a reduction in pressure in certain of said passageways starting with the last of said diffusers, and establish an unbalanced pressure on opposite faces thereof, progressively rendering said diffusers active or to progressively block said passageways starting with the first of said diffusers and balance pressure thereon, progressively rendering said diffusers inactive.

8. A multistage fluid pump comprising a housing, an inlet into and an outlet from said housing, a drive shaft journaled in said housing, a plurality of impellers spaced along said shaft and driven thereby, a plurality of diffusers freely mounted on said shaft between said impellers, for free rotation with respect thereto, the first of said diffusers having a plurality of vanes and being of a lesser diameter than the remaining diffusers, and said housing having a plurality of stationary diffusing vanes communicating with said vanes of said first diffuser, and assuring partial activation of the first stage of the pump at all times, said housing also having wall portions extending along the faces of said diffusers opposite from said impellers, fluid passageways through said wall portions, a distributor valve operable to reduce the pressure in said passageways and on the sides of said diffusers adjacent said wall portions, to hold said diffusers from

rotation and activate said diffusers by the differential in pressure thereon, and to block said passageways to balance the pressure on opposite sides of said diffusers and permit said diffusers to freely rotate about said shaft, a fluid pressure connection from said inlet to said distributor valve, for creating a reduced pressure therein, a restricted orifice in said outlet, fluid pressure operated valve means operated by variations in pressure across said orifice from a predetermined constant pressure drop, a fluid pressure connection from the first stage of said pump to said last mentioned valve means, and fluid pressure connections from said valve means to said distributor valve to effect operation thereof by pressure derived from the first stage of the pump and the progressive activation or deactivation of the stages of the pump.

9. A multistage centrifugal pump having an inlet and a discharge outlet, a plurality of coaxial impellers and associated rotatable diffusers forming the stages of the pump, means reacting against said diffusers and holding said diffusers from rotation upon an unbalanced pressure thereon, a restricted orifice in said discharge outlet, and fluid operated valve means connected between said inlet and said diffusers and establishing fluid communication therewith from said inlet and operated solely by variations in pressure drop across said orifice from a predetermined constant pressure drop, for unbalancing the pressure on opposite faces of certain of said diffusers to effect activation of said diffusers by reaction against said reaction means and render the associated stages of the pump active, and to accommodate the pressure on opposite faces of certain of said diffusers to balance and become active.

10. A multistage centrifugal pump having an inlet, a discharge outlet, a plurality of coaxial impellers and associated rotatable diffusers forming the stages of the pump, means reacting against the opposite sides of said diffusers from said impellers, to hold said diffusers from rotation by frictional engagement therewith, servo-control means connected with said inlet and said outlet, spring means balancing said servo-control means in accordance with the desired pressure rise across said inlet and said outlet, and valve means connected with said inlet and establishing fluid communication with the sides of said diffusers adjacent said reaction means and operable by said servo-control means for creating a differential in pressure on opposite sides of certain of said diffusers, to accommodate the pressure on the sides of said diffusers adjacent the associated impeller to engage said diffusers with said reaction means and render the associated stage of the pump active, and for accommodating the pressure on opposite sides of certain of said diffusers to come into balance and freely rotate with the associated impellers, rendering the associated stages of the pump inactive.

11. In a varying speed constant delivery volume fluid pump, a housing, an inlet into said housing, an outlet therefrom, a drive shaft journaled therein, an impeller on said shaft, a diffuser at the discharge side of said impeller and journaled on said shaft for free rotation with respect thereto and for limited movement therewith into frictional engagement with said housing, a restricted orifice in said outlet, fluid pressure lines leading from opposite sides of said orifice and fluid pressure operated means connected with said fluid pressure lines and operated by the

difference in pressure on opposite sides of said orifice and having fluid communication with the side of said diffuser adjacent said housing for unbalancing the pressure on opposite sides of said diffuser and accommodating said diffuser to move into frictional engagement with said housing by the unbalanced pressure acting thereon, to activate the pump.

12. In a fluid pump, a housing, an inlet into said housing, an outlet therefrom, a drive shaft journaled therein, an impeller on said shaft in communication with said inlet, a partially activated diffuser including a plurality of stationary diffusing vanes in communication with the discharge of said impeller, and a plurality of rotatable diffusing vanes forming continuations of said stationary vanes, reaction means extending along one side of said rotatable diffusing vanes and engaged thereby to frictionally hold said vanes from rotation upon unbalanced pressure thereon, a restricted orifice in said outlet, fluid pressure lines leading from opposite sides of said orifice and fluid pressure operated means connected with said fluid pressure lines and operable upon variations in rate of flow in said outlet from a predetermined flow rate and having fluid communication with said rotatable diffusing vanes on the same side thereof as said reaction means, to establish a differential in pressure on opposite sides of said rotatable diffusing vanes and accommodate said vanes to frictionally engage said reaction means and be held from rotation thereby, and render said rotatable diffusing vanes active.

13. In a constant delivery volume fluid pump, a housing, an inlet into said housing, an outlet therefrom, a shaft journaled therein, an impeller on said shaft in communication with said inlet and rotatably driven by said shaft, a partially activated diffuser including a plurality of stationary diffusing vanes in communication with the discharge of said impeller and a plurality of rotatable diffusing vanes journaled on said shaft and forming continuations of said stationary vanes, a stationary member, engaged by said rotatable vanes upon an unbalance of pressure thereon and frictionally holding said vanes from rotation, a restricted orifice in said outlet, and fluid pressure valve means connected between said inlet and said rotatable diffusing vanes and operable by variations in pressure drop across said orifice for establishing communication from said inlet to stationary vanes and unbalance the pressure thereon and accommodate said vanes to engage said reaction means to render said diffuser vanes active, and to balance the pressure on said vanes and accommodate said vanes to freely rotate on said shaft.

14. A multi-stage centrifugal pump having an inlet, a discharge outlet, an impeller shaft, a plurality of coaxial impellers spaced along such shaft and rotatably driven thereby, a separate diffuser in association with each impeller and freely mounted on said shaft, said impellers and associated diffusers forming the stages of the pump, and fluid pressure operated means operable by variations in rate of flow of fluid in said discharge outlet from a predetermined rate of flow to unbalance the pressure on certain of said diffusers and thereby hold said diffusers from rotation and activate the associated stages of the pump, and to balance the pressure on said diffusers and accommodate said diffusers to freely rotate and render the associated stages of the pump inactive, comprising fluid pressure means

connected with the opposite faces of said diffusers from the associated impellers, to balance the pressure thereon, and valve means operable by variations in rate of flow of fluid through said discharge outlet, for supplying or releasing pressure from said fluid pressure means.

15. A multi-stage centrifugal pump having an inlet and a discharge outlet, an impeller shaft, a plurality of coaxial impellers on said impeller shaft and rotatably driven thereby, a stationary diffuser associated with one of said impellers and a plurality of rotatable diffusers freely mounted on said impeller shaft in association with the other of said impellers, and means operable to unbalance the pressure on certain of said rotatable diffusers and thereby effect the holding of said diffusers from rotation and to balance the pressure thereon and accommodate said diffusers for free rotation comprising servo-control means operable by variations in rate of flow in said discharge outlet from a predetermined flow rate, and fluid operated valve means operated by said servo-control means and connected with said diffusers to relieve fluid pressure from one side thereof and unbalance pressure thereon and progressively activate said diffusers.

16. A multi-stage centrifugal pump having an inlet and a discharge outlet, a power driven impeller shaft, a plurality of coaxial impellers and associated diffusers on said shaft and forming the stages of the pump, said impellers being secured to said shaft and rotatably driven thereby and said diffusers being freely rotatable on said shaft and being axially movable therealong, and valve means connected with said inlet and establishing communication from said inlet to said diffusers and being operable solely by variations in rate of flow in said discharge outlet from a predetermined constant rate of flow, for unbalancing the pressure on opposite faces of certain of said diffusers to effect the holding of the respective diffusers from rotation and render the associated stages of pump active, and to balance the pressure on opposite faces of certain of said diffusers and effect the free rotation of said diffusers with the associated impellers, and render the associated stages of the pump active.

17. In a fluid pump, a housing, an inlet into said housing, an outlet therefrom, a power driven impeller shaft journaled in said housing, an impeller on said shaft and rotated thereby and having fluid communication with said inlet, a partially activated diffuser in communication with said impeller including a plurality of stationary radial diffusing vanes in said housing, associated with and in communication with the discharge of said impeller and rotatable diffusing vanes forming an inward continuation of said stationary vanes and mounted on said shaft for free rotation with respect thereto, a restricted orifice in said outlet, a fluid pressure passageway having fluid communication with the opposite sides of said rotatable diffuser vanes from said impeller, and pressure operated valve means operable by variations in pressure drop across said orifice, to supply fluid pressure to said rotatable diffusing vanes and balance the pressure thereon and accommodate said vanes to freely rotate with said impeller and to unbalance the pressure on said diffusing vanes to effect the holding of said vanes from rotation by the differential in pressure acting thereon, and render said rotatable diffusing vanes active.

18. A multi-stage fluid pump comprising a housing, an inlet into said housing, an outlet from

said housing, an impeller shaft journaled in said housing and having a plurality of alternately arranged impellers and diffusers thereon, each impeller being secured to said shaft and rotatably driven thereby and each diffuser being associated with an impeller and being freely mounted on said shaft, and means operable to progressively hold said diffusers from rotation and render the stages of the pump active comprising a restricted orifice in said outlet, servo-control means operable by variations in pressure drop across said orifice from a predetermined pressure drop, valve means operable by said servo-control means, and fluid pressure passageways leading from said valve means to the opposite sides of said diffusers from said impellers for releasing pressure therefrom and unbalancing pressure thereon, to effect the holding of said diffusers from rotation, and for balancing the pressure thereon to accommodate free rotation of said diffusers.

19. A multi-stage fluid pump comprising a housing having an inlet and outlet, a drive shaft journaled in said housing, a plurality of impellers spaced along said shaft and driven thereby, a plurality of diffusers mounted on said shaft between said impellers for free rotation with respect thereto and for movement therealong, the first of said impellers communicating with said inlet and the last of said diffusers communicating with said outlet, the first of said diffusers being of lesser diameter than the remaining diffusers, said casing having a plurality of stationary vanes therein forming an outward continuation of said first diffuser, assuring partial activation of the first stage of the pump at all times, abutment faces engageable by said diffusers, fluid pressure passageways leading to the sides of said diffusers adjacent said abutment faces, for balancing the pressure thereon and accommodating said diffusers to freely rotate and for unbalancing the pressure thereon to effect engagement of said diffusers with said abutment faces, valve means controlling the passage of fluid under pressure to said fluid pressure passageways, and servo-control means operated by variations in the rate of flow in said outlet for progressively operating with said valve means to progressively unbalance and balance the pressure on opposite sides thereof and render the stages of the pump active and inactive.

20. A multi-stage centrifugal pump having an inlet and a discharge outlet, an impeller shaft, a plurality of coaxial impellers mounted on said impeller shaft and rotatably driven thereby, a diffuser associated with each impeller and mounted on said impeller shaft for free rotation with respect thereto and for axial movement therealong, each impeller and associated diffuser forming a stage of the pump, and means operable by variation in pressure rise across said inlet and outlet from a predetermined constant pressure rise, to activate or inactivate certain stages of the pump including a servo-control means, means establishing fluid communication from said inlet and said outlet to said servo-control means for operating the same, spring means acting on said servo-control means and balancing the inlet and outlet pressure thereon, valve means operated by said servo-control means and connected with said inlet, separate fluid passageways connecting said valve means with each diffuser, said valve means being operable to successively connect said passageways from said inlet to said diffusers and balance pressure on said diffusers and accommodate said diffusers to freely rotate, and to

19

relieve inlet pressure from said passageways and unbalance pressure thereon and accommodate movement of said diffusers axially of said shaft, to effect the holding of said diffusers from rotation to render the associated stages of the pump active until balancing of said servo-control means by said spring means.
